FOREIGN PATENT DOCUMENTS

JP 5-176433 7/1993

Primary Examiner — Daniel Bui(74) *Attorney, Agent, or Firm* — Garner, Linn, Burkhardt & Flory, LLP(57) **CLAIM**

The ornamental design for an electrical bus bar, as shown and described.

DESCRIPTION

FIG. 1 is a bottom perspective view of an electrical bus bar showing our new design;

FIG. 2 is a top perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a front perspective view thereof, shown in use condition; and,

FIG. 10 is another front perspective view thereof, shown in use condition.

In the drawings, the broken lines depict unclaimed subject matter only and form no part of the claimed design.
